HERBERT B. MUELLER.
BY *Martin O. Smith Atty.*

UNITED STATES PATENT OFFICE

2,102,086

PORTABLE DANCE FLOOR

Herbert B. Mueller, Los Angeles, Calif.

Application December 24, 1936, Serial No. 117,638

12 Claims.

(Cl. 20—6)

My invention relates to a portable dance floor or mat of the particular type disclosed in United States Letters Patent No. 2,019,692, issued to me November 5, 1935.

The principal objects of my present invention are to generally improve upon and simplify the construction of the dance floor disclosed in my aforesaid patent, as well as other existing forms of portable or sectional dance floors; further, to provide a floor section or unit that comprises three parts of equal size and approximately uniform in construction, said parts being connected to each other by hinges that permit the members or parts to be swung both upwardly and downwardly so as to overlie or underlie the intermediate part or member; and, further, to provide improved means for connecting the edges of the sections or panels when a number of the same are assembled to form a dance floor or mat.

Further objects of my invention are to provide a dance floor panel or section that is composed of a plurality of strips of material, preferably wood, that are held together by rods that pass through the assembled strips adjacent the ends thereof, and which rods have associated therewith coil springs that are effective in maintaining tight joints between the strips and at the same time to provide the necessary degree of flexibility between said strips as the same are subjected to strains and stresses due to the varying pressures impressed on the upper surface of the floor while the same is in use; and, further, to provide an improved tongue and groove joint between the strips that make up the sections of the floor and which improved form of joint in addition to firmly retaining the strips in assembled relation, has the effect of materially increasing and more clearly defining the sound produced when the floor is used by tap dancers, and especially when such dancers are appearing before a sound recording apparatus that is utilized in connection with motion picture cameras or radio broadcasting systems.

With the foregoing and other objects in view my invention consists in certain novel features of construction and arrangements of parts that will be hereinafter more fully described and claimed and illustrated in the accompanying drawing, in which:

Fig. 1 is a top plan view of a dance floor panel constructed in accordance with my invention, and which panel is composed of three parts or sections, and also showing the end portion of an adjacent panel or floor member.

Fig. 2 is an enlarged transverse section taken

approximately on the line 2—2 of Fig. 1 and showing one of the sections folded into position beneath the intermediate section.

Fig. 3 is an enlarged detail view taken approximately on the line 3—3 of Fig. 1 and showing the rod that passes through the strips from which the floor is constructed.

Fig. 4 is an enlarged detail view showing the form of tongue and groove joint utilized between the floor strips.

Fig. 5 is an enlarged horizontal section taken approximately on the line 5—5 of Fig. 2, and showing the hinge between the folding sections.

Fig. 6 is an enlarged detail section taken on the line 6—6 of Fig. 1, as it would appear if an adjacent unit were in place.

Fig. 7 is a horizontal section taken on the line 7—7 of Fig. 6.

In the accompanying drawing I have illustrated my improved floor or mat panel composed of three sections that are designated by the letters A, B and C, and which sections are identical in size and practically identical in construction.

Each section of the floor member or panel is made up of a plurality of strips 10 of relatively thin material, such as hard wood, laid edge to edge, one edge of each strip being provided with a longitudinally disposed groove 11 and the other edge of said strip being provided with a longitudinally disposed tongue 12 that is of such size as to completely fill the complementary groove.

The faces 13 on the edges of the strips above and below the tongues and grooves are correspondingly inclined and when the strips are fitted together with the tongues 12 completely filling the grooves 11, the slightly inclined faces 13 are slightly spaced apart as illustrated by dotted lines in Fig. 4.

This particular construction provides a strong and substantial joint between the strips and I have found in practice that such a form of joint as compared to the standard or conventional tongue and groove joint produces highly desirable results in dance floor constructions, and particularly for increasing and more clearly defining the sound when the floor is used by tap dancers.

The series of strips 10 forming each section of the floor member or panel are secured in assembled relation by small metal rods 14 that extend transversely through said strips parallel with their ends, and one end of each rod carries a head 15 that occupies a recess 16 formed in the outer edge of the strip on one side of the section.

The opposite end of the rod 14 is threaded for

the reception of a tubular nut 17 that occupies a recess 18 formed in the strip on the opposite side of the section from the strip in which the recess 16 is formed.

5 Positioned within recess 18 behind the nut 17 is an expansive spring 19 that yieldingly holds the strips in assembled relation and permits a certain degree of flexibility thereof as said strips are subjected to varying degrees of pressure on 10 their upper surfaces.

In order that a number of the floor members or panels may be assembled to form a large floor, the strip 10 at one end of the panel carries on its outer edge a tongue 12, and the outer edge of the strip 15 at the opposite end of the panel is provided with one of the grooves 11 for the reception of the tongue on the next adjacent floor member or panel.

The ends of the strips 10 on one side of the floor 20 member or panel are provided with tongues 12a and the ends of the strips on the opposite side of the panel are provided with grooves 11a for the reception of the tongues 12a on the next adjacent panel.

25 In order that the end sections A and C of each panel may be folded either onto the top of or beneath the intermediate section B, the inner edges of the end sections A and C are connected to the side edges of intermediate section B by specially 30 formed hinges that are illustrated in Figs. 2 and 5. Each hinge comprises a link 20, the ends of which are connected by pins 21 to blocks 22 and 23. Block 22 is arranged for sliding movement 35 through a bearing 24 that is preferably formed of thin sheet metal, and which occupies a recess formed in the edge of one of the strips 10 and projecting upwardly and downwardly from the intermediate portions of the walls of the housing 24 are lips 25 that extend to the upper and 40 lower faces of the strip in which said housing is seated.

Suitably secured to block 22 is a short metal rod or pin 26 that passes through the strip 10 in which housing 24 is seated, and the opposite 45 end of said pin is threaded for the reception of a tubular nut 27. This nut occupies a recess 28 that is formed in strip 10 and mounted on the rod within said recess behind the nut 27 is an expansive coil spring 29.

50 Block 23 is seated in a recess 30 that is formed in the side strip of the adjacent section and secured to said block is a rod or pin 31 that extends through the strip in which the block 23 is seated. The end of rod 31 is threaded for the 55 reception of a tubular nut 32 that occupies a recess in the edge of the strip opposite the edge in which block 23 is seated.

This particular construction of hinge permits the end sections A and C of the floor member or 60 panel to be folded over onto the top of or beneath the intermediate section B, and thus affords convenience when the floor members or panels are being packed for storage or transportation or while being assembled to form a dance floor or 65 disassembled after use.

When the end sections A and C are folded over 70 onto the intermediate section, the blocks 22 of the hinges will move through the housings 28 following the swinging movement of the end sections, and as such movement takes place the nuts 27 on the ends of the rods 26 will move inwardly through the recesses 28, thereby compressing the springs 29. The springs 29 are utilized for maintaining the hinge connections between the sections normally under tension, and this tension

may be regulated by proper manipulation of the nuts 27.

The nuts 17 on the ends of the rods 14, as well as the nuts 27 and 32, are provided in their outer ends with slots 27a for the reception of a screwdriver or like tool that is used in screwing the nuts onto or off the ends of the rods on which they are seated.

When a number of the floor members or panels are assembled to form a floor of large area, the 10 edges of said panels are united to hold the same in assembled relation by means of hooks 33 that are illustrated in Figs. 6 and 7. One or more of these hooks are located in the strip 10 at one end of the panel, and said hooks are adapted to enter 15 recesses such as 34 that are formed in the strip 10 at the opposite end of the panel.

Seated in the strip 10 and passing through the recess 34 is a pin 35 that is engaged by the hook 33 when the same is swung outwardly to secure 20 the edges of two adjacent floor members or panels to each other. Each hook 33 is mounted for operation within a recess 36 that is formed in the end strip 10 of the panel and passing through the inner end portion of the hook is a square or non-circular 25 tube 37. Surrounding the end portions of the tube 37 that project above and below the hook 33 are circular disks or washers 38 that are mounted for rotation in corresponding apertures 39 that are formed in the strip 10 above and below the 30 recess 36.

The ends of the rectangular tube 37 and the washers 38 are flush with the upper and lower faces of the strip in which the hook is seated. The tube 37 is made non-circular in order that 35 it may receive a correspondingly shaped wrench when the hook is to be swung from one position to another.

As illustrated in Fig. 1, I prefer to provide one hook at one end of each floor member or panel, 40 and a corresponding recess 34 and pin 35 at the opposite end of said member or panel, and, further, to provide the sections A and B at one end with a hook and a corresponding recess and pin at the opposite end.

The arrangement of hooks has been found to be 45 amply sufficient to hold the floor members or panels in assembled relation when a number of such panels are used in forming a dance floor or mat, and while not in use the hooks 33 are swung 50 into their recesses 36, as illustrated in dotted lines in Fig. 7.

The hinged sections forming the floor member or panel, may be easily and conveniently folded together so that the floor members are readily 55 portable and may be conveniently packed for storage or transportation and likewise conveniently opened and assembled for use. The connections between the strips forming the sections and hinges between the said sections provide a 60 strong and substantial structure and at the same time such connections produce a limited degree of flexibility which is essential in a portable dance floor or mat.

The construction of the joints between the 65 strips forming the hinged sections is effective in holding the strips properly in assembled relation and at the same time such construction materially increases and intensifies the sound produced when the floor is used by tap dancers. 70

While I have shown and described the floor or mat member composed of three panels, it will be understood that my invention contemplates the provision of a single panel having the edges of the strips connected by my improved form of 75

tongue and groove joint, and the strips forming the panels being held in assembled relation by the rods 14 with which are associated the expansive springs 19.

5. Further, my invention contemplates the provision of floor or mat members comprising two panels hinged to each other, or any number of panels in excess of three.

It will be understood that minor changes in the 10 size, form and construction of the various parts of my improved portable dance floor may be made and substituted for those herein shown and described without departing from the spirit of my invention, the scope of which is set forth in the 15 appended claims.

I claim as my invention:

1. In a portable dance floor or mat, a panel 20 composed of three sections of equal size and shape, double-acting hinges connecting the end sections with the intermediate section so that said end sections may be folded onto the top or bottom of said intermediate section, and means mounted in the panel adjacent the edges thereof for securing a number of the panels to each other 25 in assembled relation.

2. In a portable dance floor or mat, a panel formed in three sections of substantially equal size and shape, each section comprising a plurality of narrow strips of thin material, the edges of 30 which are provided with tongue and groove joints, means extending through the strips of each section to hold the same in assembled relation, and double-acting hinges connecting the end sections and the intermediate section whereby the end 35 sections may be folded over onto the top or bottom surfaces of said intermediate section.

3. A portable dance floor or mat as set forth in claim 2, and with means seated in the panel adjacent its edges for securing a number of said 40 panels to each other in assembled relation.

4. In a portable dance floor or mat, a panel composed of three sections of substantially equal size and shape, double-acting hinges connecting the end sections to the intermediate section, each 45 section composed of a plurality of thin narrow strips of material, the edges of said strips being provided with tongue and groove joints, and those portions of the edges of the joints above and below the tongues and grooves being spaced apart when the joints are assembled.

5. In a portable dance floor or mat, a panel composed of three sections of substantially equal size and shape, double-acting hinges connecting the end sections to the intermediate section, each 55 section composed of a plurality of thin narrow strips of material, the edges of said strips being provided with tongue and groove joints, the tongues of said joints completely filling the grooves when the joints are assembled, and those 60 portions of the edges of the strips above and below the tongues and grooves being spaced apart when the joints are assembled.

6. In a portable dance floor mat, a unit com-

posed of three sections of substantially equal size and shape, double-acting hinges connecting the end sections with the intermediate section, each section comprising a plurality of thin narrow strips of material, rods extending through the strips of each section for holding the same in assembled relation, a head formed on one end of each rod, a nut screw seated on the other end of said rod, there being a recess formed in the section for the accommodation of said nut, and an expansive coil spring located on the rod within 10 said recess behind the said nut.

7. In a portable dance floor or mat, a unit composed of three sections of substantially equal size and shape, double-acting hinges connecting the 15 end sections with the intermediate section, each hinge including a pair of blocks and a link connecting said blocks, a bearing for one of said blocks, and means for yieldingly resisting the movement of said block through said bearing.

8. In a portable dance floor or mat, a unit composed of three sections of substantially equal size and shape, each section composed of a plurality of narrow strips of thin material, the edges of each set of strips being provided with tongue and 20 groove joints, means passing through the strips of each section to hold the same in assembled relation, double-acting hinges connecting the end sections with the intermediate section, one member of each hinge being mounted for sliding movement through the strip in which it is seated, and means for yieldingly resisting the sliding movement of said hinge member in one direction.

9. A portable dance floor or mat as set forth in claim 8, and with means seated in the panel 35 adjacent its edges for securing a number of the panels to each other in assembled relation.

10. In a portable dance floor, a panel composed of a plurality of thin narrow strips of material, the edges of which strips being connected by tongue and groove joints and those portions of the edges of the strips above the tongues and 40 grooves being spaced apart when the joints are assembled.

11. In a portable dance floor, a panel composed of a plurality of thin narrow strips of material, the edges of which strips being connected by tongue and groove joints, those portions of the edges of the strips above the tongues and grooves being 45 spaced apart when the joints are assembled, and the tongues of said joints completely filling the grooves when the joints are assembled.

12. In a portable dance floor or mat, a panel composed of a plurality of narrow strips of thin material, the edges of which are provided with 55 tongue and groove joints, rods passing through all of the strips of the panel for holding the same in assembled relation, a nut screw seated on one end of each rod, there being a recess formed in the panel for the accommodation of said nut, and an 60 expansive coil spring located on the rod within said recess behind said nut.

HERBERT B. MUELLER.
